UNITED STATES PATENT OFFICE.

JEPHTHA L. HOLTON, OF STEUBENVILLE, OHIO, ASSIGNOR TO GILL BROTHERS COMPANY, OF STEUBENVILLE, OHIO, A CORPORATION OF WEST VIRGINIA.

DESIGN FOR A REFLECTOR-SHADE.

45,633.

Specification for Design.

Patented Apr. 21, 1914.

Application filed January 24, 1914. Serial No. 814,248. Term of patent 7 years.

To all whom it may concern:

Be it known that I, JEPHTHA L. HOLTON, a citizen of the United States of America, and a resident of Steubenville, county of Jefferson, State of Ohio, have invented a certain new, original, and ornamental Design for a Reflector-Shade, of which the following is a specification.

Referring to the drawings—Figure 1 is an elevation showing the bowl in upright position. Fig. 2 is a horizontal section on the line 2, 2 of Fig. 1. Fig. 3 is a fragmentary horizontal section on the line 3, 3 of Fig. 1.

The device consists of a shade 1, the exterior surface of which is fluted, the flutes being vertical, *i. e.*, extending in the direction of the corresponding meridians of the bowl and being slightly curved or approximately flat in a transverse plane, and arranged in two series, the upper series 2 covering substantially the entire surface of the shade above the hip 3, and the lower series 4 covering the remainder of the surface below the hip. The flutes of the two series are equal in number and alternately placed, the

lines 5 and 6 separating the adjacent flutes of one series bisecting the corresponding flutes of the other series. The two series of flutes 2 and 4 meet in a broken or saw-tooth line 7 encircling the hip of the shade.

I claim:

The ornamental design for a shade bowl having two series of substantially flat, meridional flutes, the upper series covering the entire surface of the shade above the hip line, the lower series covering the surface below the hip line, the flutes of the two series being alternately placed so that the lines separating the adjacent flutes of one series bisect the flutes of the other series, and the surfaces of the two sets of flutes meet in a saw-tooth line encircling the hip of the shade substantially as shown and described.

Signed by me at Steubenville, Ohio, this 20th day of January, 1914.

JEPHTHA L. HOLTON.
